UNITED STATES PATENT OFFICE.

NAGEEB T. HASHIM, OF MANILA, PHILIPPINE ISLANDS.

STONE-BLOCK-SAWING MACHINE.

Application filed December 18, 1924. Serial No. 756,793.

To all whom it may concern:

Be it known that NAGEEB T. HASHIM, a citizen of the United States, residing at Manila, in the Philippine Islands, has invented certain new and useful Improvements in Stone-Block-Sawing Machines, of which the following is a specification.

My invention relates broadly to stone sawing machines, and more particularly to machines of this character designed to saw building blocks from Dubie stone, or other similar naturally occurring stone formations.

The primary object of my machine is to provide such a machine, which is capable of performing all the operations, necessary to cut the rock into the desired size blocks, from the natural deposits.

Another object of my invention is to so arrange the operative parts of the machine that they may be readily adjusted to effect the desired cuts into the surface of the stone bed to form the side and ends of the blocks, and also to undercut the blocks, thus formed, to sever them from the natural deposits.

A further object of my invention is to provide a machine of the character described, that is adapted to travel over the surface of the natural stone deposit during the operations of cutting and severing blocks of desired shape and size therefrom.

A still further object of my invention is to so arrange the operative parts of the machine, in relation to the driving mechanism, that all operative parts may be driven from a single power plant and readily controlled by a single operator.

A further object of my invention resides in the novel construction of the stone-cutting machine, whereby the maximum number of blocks may be cut from a quarry at each setting of the machine, and with the minimum labor and expense.

It will be understood that the machine forming the subject matter of this application is designed to cut predetermined size blocks from the top surface of a stone quarry, and that the machine is adapted to travel over the surface of the quarry during the various steps of cutting and severing the blocks therefrom. The machine is designed particularly to cut building blocks from natural deposits of Dubie rock such as is found in the Philippines. This Dubie rock, which resembles sandstone, is found in large deposits practically at the surface

of the ground, so that it is only necessary to remove the sod, in most instances, to expose the upper surface of the rock bed.

Referring now to the drawings which are made a part of this specification, and on which similar reference characters indicate similar parts;

Fig. 1 is a side elevation of my improved stone block sawing machine, showing the side of the machine on which the operator rides during the operation of the machine, and the positioning of the various controls in convenient reach of the operator.

Fig. 2 is a side elevation of the other side of the machine, illustrating the power plant and driving connections associated therewith.

Fig. 3 is an end elevation, partly in section, showing, in detail, one of the stone saw carriages, and its relation to the operative parts of the machine.

Fig. 4 is a fragmentary view of a portion of the machine which is not clearly shown in Fig. 3.

Fig. 5 is a diagrammatic view, illustrating the stone sawing machine in the operation of making lateral cuts in the upper surface of the stone bed to form the ends of the blocks.

Fig. 6 is a view, similar to Fig. 5, of the opposite end of the quarry, illustrating the machine in the operation of making the last of the series of lateral cuts.

Fig. 7 is a diagrammatic view illustrating the machine equipped to make longitudinal cuts in the surface of the stone bed.

Fig. 8 is a view, similar to Fig. 7, of the machine in the operation of making the last of the series of longitudinal cuts.

Fig. 9 is a diagrammatic view, illustrating the stone sawing machine equipped and in position to undercut the first line of blocks which has been formed by the steps previously illustrated.

Fig. 10 is a view, similar to Fig. 9, of the machine in the operation of severing the last line of blocks.

Fig. 11 is a sectional view taken through the quarry to illustrate the machine in elevation and adjusted to the position illustrated in Fig. 9, and,

Fig. 12 is a diagrammatic plan view of the quarry illustrating the track rails laid on the lower surface of the stone bed from which blocks of stone have been removed by the steps previously illustrated, and the

machine removed from the rails, to show the layout of the opposite side of the quarry on the return operation of the machine across the quarry.

- 5 Referring to Figs. 1 to 4 inclusive, the portions indicated as A, represent the main frame of the stone block sawing machine, the base or chassis of which is composed of side channel irons 1 and 1', and end channel irons 2 and 2' which are bolted, or otherwise rigidly secured together, at the four corners. Journal boxes 3 are secured to the side channel irons 1 and 1' and provide bearings for axles 4 and 4' which extend transversely between the two channel irons 1 and 1'. Secured on the axles 4 and 4' are wheels 5, adapted to travel on a conventional form of track rail 6.

Secured on the axle 4, between the side channel irons 1 and 1', is a sprocket wheel 7 having a driving connection with the sprocket wheel 8, secured to the transverse shaft 9, through the sprocket chain 10. A gear 11 is secured on the outer end of the shaft 9 and is driven through a train of reduction gears 12, 13, 14, 15 and 16 from the beveled gear 17. The beveled gear 17 is in turn driven from the gear 18, secured to the lower extremity of the vertical drive shaft 19, which is mounted in journal bearings 20 and 20' secured to the side of the main frame A. A frictional gear element 21, adapted to operate across the face of the cooperating frictional gear element 22, mounted on driven shaft 29, is slidably mounted on the vertical drive shaft 19, and operatively connected therewith, through the key way 23, in the shaft 19. An operating lever 24, having a yoke 25 operatively engaging the frictional gear element 21, serves to adjust the gear element 21, relative to the gear element 22, by means of the hand lever 26, to rotate the vertical drive shaft 19 at variable speeds in either forward or reverse directions, as will be readily understood.

Centrally mounted on the main frame A is a motor B, having a rotary drive shaft 27 which carries a pinion 28. Transverse shafts 29 and 29' are suitably journaled on supports 30 and 30' in the frame on each side of the motor B, and carry reduction gears 31 and 31' which mesh with the centrally arranged pinion gear 28. Clutch elements 32, slidably mounted on the transverse shafts 29 and 29', are adapted to be manually operated by the hand levers 33 and 33' to drive the shafts from the reduction gears 31 and 31'.

Also mounted on the transverse shafts 29 and 29' are small pinion gears 34 and 34' which mesh respectively with reduction gears 35 and 35', carried on driven shafts 36 and 36'. Pinion gears 37 and 37' are also carried on the shafts 36 and 36' which mesh with reduction gears 38 and 38', se-

cured on the ends of transverse shafts 39 and 39'. Secured on the opposite ends of the shafts 39 and 39' are beveled gears 40 and 40' which mesh respectively with gears 41 and 41'. The gears 41 and 41' are each formed with a tubular extension 42 and 42' which are suitably journaled in the frame of the machine and through which vertical drive shafts 43 and 43', formed with key ways 44 and 44', are adapted to extend. The vertical drive shafts 43 and 43', are each mounted in suitable journals 45 and 45', secured to the frame, and carry beveled gears 46 and 46' at their lower extremities. The beveled gears 46 and 46' mesh respectively with gears 47 and 47' which are formed with tubular extensions 48 and 48', suitably journaled in guide frames which will be described hereafter. Transverse shafts 49 and 49' formed with key ways 50, are adapted to slide through the tubular extensions 48 and 48' of the gears 47 and 47', and to be driven thereby.

On each end of the machine frame A, are provided vertical screw shafts 51 and 52 and 51' and 52' suitably journaled at their lower extremities in thrust bearings 53 and 54 and 53' and 54' (see Fig. 4), and journaled adjacent their upper ends in the machine frame. Adjustably supported on each pair of the screw shafts 51 and 52 and 51' and 52', at each end of the machine frame, are transverse guide frames 55 and 55'. These guide frames consist mainly of parallel channel irons 56 and 57 and 56' and 57', which extend out beyond the sides of the frame A, and are rigidly secured together by suitable cross members, and serve to slidably support saw carriages 58 and 58', as will be readily understood by reference to Figs. 1 and 3.

As shown in these Figures 1 and 3, the channel iron 56 and 57 and 56' and 57' are each formed with flange plates 59 and 60 and 59' and 60', secured to the lower edge thereof on which the saw carriages 58 and 58' are adapted to slide. Depending from the inner end of each of the saw carriages 58 and 58', are blocks 61 (see Fig. 3), through which transverse screw shafts 62 and 62', journaled in suitable bearings in the guide frames 55 and 55', are threaded. The transverse screw shafts 62 and 62' carry gears 63 and 63', which mesh respectively with gears 64 and 64' on counter shafts 65 and 65'. Beveled gears 66 and 66' are secured to the outer ends of the counter shafts 65 and 65' and mesh respectively with gears 67 and 67' secured to the lower ends of the vertical drive shafts 68 and 68'. The vertical drive shafts 68 and 68' are formed with key ways 69 and 69', which are slidably engaged by frictional gear elements 70 and 70', mounted respectively on the vertical shafts 68 and 68', and are adapted to be

driven at variable speeds, in either forward or reverse directions, by frictional gear elements 71 and 71', mounted on the outer ends of driven shafts 36 and 36'. The frictional gear elements 70 and 70' are adapted to be adjusted across the faces of the frictional gear elements 71 and 71', by means of the levers 72 and 72' and hand levers 73 and 73'.

Depending from points adjacent the outer end of the saw carriages 58 and 58' are a pair of spaced brackets 74 and 75 and 74' and 75', formed with journal bearings 76 and 77, at their lower end, in which are journaled shafts 78 and 78'. The shafts 78 and 78' extend through the brackets 74 and 75 and 74' and 75', and are provided with means for adjustably securing stone saws 79 and 80, shown in dotted lines in Fig. 3.

Secured on the shafts 78 and 78' between the pairs of depending brackets are sprocket wheels 81 and 81', and secured on the transverse key shafts 49 and 49', also journaled respectively in the saw carriages 58 and 58', are sprocket wheels 82 and 82'. Sprocket chains 83 and 83' connect the pairs of sprocket wheels 81 and 82 and 81' and 82' and serve to drive the shafts 78 and 78' and stone saws 79 and 80 from the mechanism previously described.

It will also be noted by reference to Figs. 1 and 3, that beveled gears 84 are also secured on the shafts 78 and 78' between the pairs of depending brackets and that swinging bracket members 85 and 85' are journaled on the shafts 78 and 78'. The swinging bracket members carry saw shafts 86 and 86' which are journaled respectively in said transverse brackets and extend at right angles to the shafts 78 and 78'. Beveled gears 87, meshing with the beveled gears 84, on the shafts 78 and 78', are secured to the inner ends of the saw shafts 86 and 86' and serve to drive the saw shafts therefrom. Stone saws 88 and 88', shown in dotted lines in Figs. 2 and 3, are detachably secured on the outer ends of the saw shafts 86 and 86', and are adapted to operate in either of two positions as is indicated in dotted lines in Fig. 3.

When the machine is operated to make cuts at right angles to the track on which the machine is adapted to travel, the swinging brackets 85 and 85' are bolted to the depending supports 89 and 89'. The supports 89 and 89' also serve to hold the swinging brackets 85 and 85' and saw shafts 86 and 86' extended when not in use. The stone saws 88 and 88' are also adapted for undercutting, and for such operation, the swinging brackets 85 and 85' are swung to the dotted line position in Fig. 3, and secured by bolts to the depending bracket bearings 76 and 77.

As heretofore explained the transverse

guide frames 58 and 58' are adjustably supported on vertical screw shafts 51 and 52 and 51' and 52'. These vertical screw shafts are adapted to be driven from the motor B to raise or lower the transverse guide frames 70 by means of worm gears 90 and 90', mounted respectively on the shafts 91 and 91'. The shafts 91 and 91' extend transversely of the machine and are journaled in suitable bearings adjacent their ends. Loosely mounted 75 on the shafts 91 and 91' are pulley wheels 92 and 93, each having a clutch face 94 and 95. Keyed to the shafts 91 and 91', between the pulley wheels, are clutch members 96, adapted to connect either of the pulley 89 wheels 92 or 93, to the respective shafts by operation of the hand levers 97 and 97'. Secured respectively on the transverse driven shafts 29 and 29' are pulley wheels 98 and 98', from which the loose pulley wheels 92 and 93 are driven in opposite directions by belts 99 and 100 and 99' and 100'. The vertical screw shafts are thereby rotated to raise or lower the saw carriages by manually adjusting the levers 97 and 97'. 99

The motor controller C, shown in Figs. 1 and 3, may be of any well known or approved construction and needs no particular description herein.

Referring now particularly to Figs. 5 to 11 inclusive, I have illustrated, more or less diagrammatically, the various steps in the operation of my improved stone block sawing machine in the quarry. As will be understood from the foregoing description, my machine is designed to cut predetermined size building blocks from Dubie rock beds, or from other natural occurring stone deposits, by making right angle cuts into the surface of the stone bed, to form the ends 100 and sides of the blocks, and thereafter undercutting the blocks thus formed, parallel to the surface of the stone bed, to sever the blocks therefrom.

It will also be understood that, prior to 110 the operations just described, and illustrated in Figs. 5 to 11 inclusive, all sod and soil, covering the stone bed, are first removed to expose the upper surface of the bed and to outline the limits of the quarry. Trenches 115 indicated at D and E are then excavated along the full extent of parallel edges of the quarry as is shown in Fig. 12. The trenches may be excavated in any convenient manner, and are made a sufficient width and depth 120 to receive the stone saws 88 and 88', as will be understood from the following description.

Track rails 6 are laid on the surface of the stone bed, a short distance from the edge 125 of the quarry and parallel with the edge X of the trench D. The stone block sawing machine, designated as A, is then mounted at one end of the track rails 6. Stone saws, such as are indicated in dotted lines, as 130

and 88', are then secured on the saw shafts 86 and 86' and the swinging brackets 85 and 85' secured to the depending supports 89 and 89', as is clearly shown in Figs. 2, 5 and 6. 5 The guide frames 55 and 55' are then adjusted vertically at each end of the machine frame A, by the operation of the vertical screw shafts 51 and 52 and 51' and 52', and the saw carriages 58 and 58' extended in 10 the guide frames by the operation of the transverse screw shafts 62 and 62'. The stone saws 88 and 88' are thus extended over the surface of the quarry and lowered into the trench D in position to make lateral cuts 15 into the surface of the quarry at right angles to the edge X of the trench, as is shown in Figs. 5 and 6. The hand levers 33 and 33' are then moved by the operator to engage the clutch elements 32, to drive the saws 20 from the motor B, and the hand levers 73 and 73' moved to adjust the friction gear elements 70 and 71, and 70' and 71', to drive the transverse screw shafts 62 and 62'. The saw carriages 58 and 58' are thus caused to 25 travel in on the guide frames 55 and 55' drawing the saws 88 and 88' toward the machine A to make the lateral cuts F in the surface of the quarry.

On the completion of each of the cuts F, 30 the rotation of the transverse screw shafts 62 and 62' is reversed to again extend the saw carriages and bring the saws out of the cuts and into the trench D. The machine A is then operated along the track rails 6, by 35 the motor B, to bring the saws into position for the next lateral cuts whereupon the operation just described is repeated.

It will be noted that each of the saws and saw carriages have independent controls, 40 and are mounted on opposite ends of the machine frame. By this construction it is possible to operate either unit independently or in conjunction with the other, permitting a greater range of operation in the quarry 45 at each setting of the machine.

In making the longitudinal cuts Y, the saws 88 and 88' are removed from the shafts 86 and 86' and pairs of saws, 79 and 80 and 79' and 80', such as are indicated in dotted lines in Figs. 3, 7 and 8, are adjusted on the saw shafts 78 and 78' and secured a predetermined distance apart. The distance between the saws 79 and 80 and 79' and 80' determine the width of the stone blocks to 55 be cut. The saw frames are then extended over the quarry to the positions shown in Fig. 7 and the saws operatively connected with the motor B as previously explained.

The saw frames are then lowered until 60 the saws have cut into the surface of the stone bed a distance equal to the depth of the blocks to be cut. The machine is then caused to travel along the track rails to the position A', indicated in dotted lines in 65 Fig. 7. The guide frame 55 is then raised

to free the saws 79 and 80 from the surface of the stone bed and the saw carriage 58 retracted to the dotted line position in this figure. The saws 79 and 80 are then lowered, as above explained, and the machine 70 again operated to travel along the rails to the opposite end of the quarry. It will be noted that four parallel cuts are made from this point to the end of the quarry; the saw carriages 58 and 58' being readily adjusted 75 back and forth to complete each pair of cuts during the operation of the machine along the track rails. This operation is repeated back and forth from end to end of the quarry until a predetermined number 80 of lines of blocks have been outlined as is shown in Fig. 8.

The machine is then brought to the position on the rails illustrated in Figs. 9 and 11, with the saw carriage 58 extended to 85 bring the swinging brackets 85 over the trench D. The stone saw 88 is again secured on the shaft 86 and the bracket 85 swung down to the dotted lines position illustrated in Fig. 3, and in full lines in 90 Fig. 11, and secured by bolts to the bearings 76 and 77 of the depending brackets 74 and 75. It will be understood that the saws 79 and 80 are removed from the shafts 78 for this operation of the machine. The 95 guide frame is then adjusted to lower the saw into position to undercut the first line of blocks and the saw set into operation. The saw carriage is then retracted until the saw has undercut the surface to the first 100 longitudinal cut Y, as is indicated in dotted lines in Fig. 9. The machine is now equipped and adjusted to be propelled along the rails to sever the first line of blocks. At the completion of each line, the saw carriage 105 is again retracted a distance equal to the width of the blocks and the friction gear elements 21 and 22 adjusted to reverse the operation of the machine along the rails.

When all the blocks in the range of the 110 machine have been cut and removed, the track rails 6 are set back for another operation of the saws. These operations are repeated across the width of the quarry until the edge of the trench E is reached. The 115 track rails are then moved forward on the previously cut lower surface, and the machine mounted on the rails with its operating side towards the trench E. In this position it will be seen that two layers of blocks 120 are removed before the rails are again set forward for repeating the operations previously explained. The machine is then operated from end to end and from side to side of the quarry during its operation of 125 cutting the ends and sides of the blocks and severing them from the rock bed until all the available rock in the quarry has been cut into predetermined size blocks and removed. 130

It will be noted from the above description of the machine and its operation in the quarry that, by adjustably mounting the saw carriages on opposite ends of the machine 5 and independently operating the elements of each saw carriage, the saws are operated to cut continuous kerfs beyond each end of the machine, and from one side of the quarry to the other at each setting of the machine.

10 By this improved machine each operation back and forth across the quarry may be of uniform length. The maximum amount of stone is thus cut into blocks at each setting of the machine, and the resulting walls of 15 the quarry are maintained substantially vertical, permitting the machine to cut itself into the stone bed until all available stone has been cut and removed.

What I claim is:

20 1. A stone block quarrying machine comprising a vehicle adapted to be propelled over the surface of a stone bed, saw carriages adjustably mounted on opposite ends of said machine, saws rotatably carried by said saw carriages to cut kerfs into the stone bed beyond the ends of the machine, and means for independently adjusting and operating said saws, whereby the work beyond the range of 25 one saw is completed by the other at each setting of the machine.

30 2. A stone block quarrying machine comprising a vehicle adapted to travel over the surface of the quarry, means for operating said vehicle, guide frames mounted on each 35 end of said vehicle to extend laterally therefrom, means for independently adjusting said guide frames vertically relative to said vehicle, saw carriages slideable horizontally in said guide members, means for independ-

ently operating said saw carriages in said 40 guide frames, saws rotatably carried by said saw carriages, and means independently operating the saws of each saw carriage to make cuts into the stone bed beyond the respective ends of said machine, whereby the 45 work beyond the range of the saws of one saw carriage is completed by the saws of the other saw carriage at each setting of the machine.

3. A machine of the character described, 50 having saw carriages adjustably mounted on opposite ends of said machine, saw shafts rotatably mounted in said saw carriages to extend at right angles to each other, means for adjusting one of said saw shafts relative to 55 the other in each of said saw carriages, saws carried by said saw shafts, and means for operating the saws of one saw carriage independently of the saws of the other saw carriage, whereby the saws of said saw carriages co-operate to produce continuous cuts 60 into the stone bed beyond the ends of said machine and from one side of said quarry to the other.

4. A stone block quarrying machine comprising a vehicle adapted to be propelled over the surface of the quarry, a saw-carrying shaft adjustably mounted on said vehicle to position its saw to make vertical cuts into the surface of the stone bed, and means for 65 adjusting said saw shaft to position its saw to undercut the surface of the stone bed at substantially right angles to the first mentioned cuts made into the surface of the 70 stone bed.

75 In testimony whereof I affix my signature.

NAGEEB T. HASHIM.
